[57] CLAIM

I claim the ornamental design for a motorized water ski, as shown and described.

DESCRIPTION

FIG. 1 is a perspective view of a motorized water ski showing my new design;

FIG. 2 top plan view thereof;

FIG. 3 is a front elevation view thereof;

FIG. 4 is a right side elevation view thereof;

FIG. 5 is a rear perspective view thereof; and,

FIG. 6 is a bottom plan view thereof; and,

FIG. 7 is a rear elevation view thereof.
